UNITED STATES PATENT OFFICE.

GEORGE AUER, OF TOLEDO, OHIO.

DESIGN FOR A SIDE-WALL REGISTER.

SPECIFICATION forming part of Design No. 35,789, dated March 4, 1902.

Application filed January 30, 1902. Serial No. 91,944. Term of patent 14 years.

To all whom it may concern:

Be it known that I, GEORGE AUER, a citizen of the United States, residing at Toledo, in the county of Lucas and State of Ohio, have invented and produced a new and original Design for a Side-Wall Register, of which the following is a specification, reference being had to the accompanying drawings, forming part thereof, in which—

Figure 1 is a front view of a side-wall register embodying my design, and Fig. 2 is an end view thereof.

The design comprises a rectangular frame A, surrounding an ornamental foliated panel B, below which frame and panel is a horizontal foliated grille or panel C. The frame A is slightly inclined from the perpendicular, its lower end projecting beyond its upper end,

so that the outer end portions D of the design appear tapered or beveled and the lower portion of the register is swelled or projects beyond the upper portion thereof, as shown in Fig. 2.

The essential features of the design are the frame and panel above the grille.

Having thus described my invention, what I therefore claim as new is—

The design for a side-wall register substantially as herein shown and described.

In testimony whereof I have signed my name to this specification in the presence of two subscribing witnesses.

GEORGE AUER.

In presence of—

T. H. ALEXANDER,
JAMES R. MANSFIELD.
